Patented Mar. 22, 1921.

FIG. 1

FIG. 2

FIG. 3

INVENTOR

J. H. MOLTHAN,

BY

Milton S. Grindall,

ATTORNEY

UNITED STATES PATENT OFFICE.

JOHN H. MOLTHAN, OF MOVILLE, IOWA.

LANTERN-BAIL.

1,372,185.

Specification of Letters Patent. Patented Mar. 22, 1921.

Application filed April 13, 1920. Serial No. 373,513.

To all whom it may concern:

Be it known that I, JOHN H. MOLTHAN, a citizen of the United States, and a resident of Mowville, in the county of Woodbury and 5 State of Iowa, have invented certain new and useful Improvements in Lantern-Bails, of which the following is a specification.

My present invention has for its primary object the production of an improved lantern bail so constructed as to be held substantially upright, to be conveniently grasped by the carrier when the lantern is setting on its base, and yet permit relative oscillation between the lantern and its bail. 10

Still another object of the invention is the production of a lantern bail, inexpensive and simple in construction, and thoroughly efficient in operation. 15

With these and other objects in view, the 20 invention, consisting in the construction, combination and novel arrangement of parts will be fully understood from the following description, reference being had to the accompanying drawings which form a part of 25 this application and in which like characters of reference indicate corresponding parts throughout the several views, of which,—

Figure 1 is a side elevation of a lantern bail constructed in accordance with my invention and applied to a lantern; 30

Fig. 2 is a front elevation thereof; and

Fig. 3 is an enlarged plan of one of the bail guides.

Although I have illustrated, and herein- 35 after described but one embodiment suitable for practising the invention, I would not be understood as being limited to the specific structure chosen for illustration, for many alterations and modifications may be made 40 in the details of construction and arrangement of parts herein disclosed, without departing from the spirit and scope of the invention, as defined in the appended claims.

Referring now to the illustrations, the 45 lantern illustrated includes tubular side frame members, 4, having their upper end portions, 5, horizontally disposed.

The bail proper consists preferably of a 50 single piece of wire folded at the approximate center and twisted upon itself for a portion of its length, as at 7, the said twisted portion being curved to form a hook, the folded end of the hook being formed with a depending eye, 8, the lower edge of which 55 is preferably beveled to provide a comparatively sharp edge, 9, the said eye being dis-

posed in a plane at substantially right angles of the plane of the hook. The untwisted portions of the wire are bent laterally in opposite directions and at right angles to 60 the plane of the hook, as at 10, the extreme end portions thereof being then bent downwardly, as at 11, and secured to the lantern as will be presently described.

On each side of the lantern I provide 65 improved means whereby the bail is secured to the lantern so as to permit free oscillation of the bail, yet limited oscillation, and when desired support it in an upright position. Each of said devices consists of a single piece of wire having its lower end portion adapted to encompass the associated frame portion, 5, as at 12, the extreme end portion of the wire being hooked or wound securely to the portion of the wire immediately above the member, 5, as at 13. The intermediate portion of the wire is formed with a lateral loop or eye, 14, which extends upwardly a distance, as at 15. The upper end portion is bent at 16, to extend a distance 70 rearwardly, as at 17, then looped over substantially in parallelism with itself and extended forwardly, as at 18, and extended forwardly of the portion, 15, substantially 75 the same distance as it is rearwardly, the remaining end portion being then bent laterally, as at 19, and twisted, as at 20, on the portion, 15, immediately below the bend, 16, thus forming a forwardly and rearwardly 80 extending loop.

The depending arms, 11, of the bail pass through the above described loop and are provided on their ends with eyes, 21, inter-linked with the eyes, 14, which it will be observed are positioned directly below the 85 guide loop. The center portion of the loop side, 18, or that portion directly opposite the bend, 16, is curved outwardly, as at 22, to provide a central recess, 23, on the inner side of the loop side, 18. The bail arms, 11, and 90 the guide loop are so constructed and related that the latter yieldably engage the loop sides, 18. Thus it is clear when the lantern sets upon its base the bail may be held substantially upright by virtue of the 95 arms, 11, being engaged in the recesses, 23, as will be seen from Fig. 3, yet the said arms are free to oscillate between the ends of the 100 guide loops.

The hook of the bail is so formed that the 110 lantern may be hung by placing the end, 9, of the hook on the surface of a ledge as in-

dicated at, 24, in which position the eye, 9, is substantially alined with the axis of the lantern, and the arms, 11, are disposed in corresponding ends of the guide loops, or if 5 desired the bail may be placed over a carrier's arm or hung on a projecting member.

Having thus described my invention, what I claim as new and desire to secure by Letters Patent of the United States is,—

- 10 1. A bail for a lantern, comprising a bail proper having depending arms and upright members adapted to be secured to the lantern and provided at their upper ends with forwardly and rearwardly extending guide slotted means and eyes therebelow, the arms being passed through the guide slots and pivoted to said eyes.
- 15 2. A bail for a lantern having horizontal frame members, comprising a bail proper having depending arms, and wires adapted to be secured at one end to and extend up-

wardly from said members, and formed at their upper ends with forwardly and rearwardly extending loops, and with intermediate eyes, the arms being passed through the 25 loops and pivoted to the eyes.

3. A bail for a lantern having horizontal frame members, comprising a bail proper having depending arms, and wires adapted to be secured at one end to and extend up- 30 wardly from said members, and formed at their upper ends with forwardly and rearwardly extending loops, and with intermediate eyes, the arms being passed through the loops and pivoted to the eyes whereby the 35 arms may oscillate in the loops, a side of each loop being shouldered to yieldably engage the associated arm to hold the bail in an upright position.

In testimony whereof I have hereunto set 40 my hand this 20th day of March, 1920.

JOHN H. MOLTHAN.
